UNITED STATES PATENT OFFICE.

ALLAN CUNNINGHAM, OF SEATTLE, WASHINGTON.

TOWING MACHINE AND METHOD OF TOWING.

1,414,724.

Specification of Letters Patent.

Patented May 2, 1922.

Application filed November 22, 1920. Serial No. 425,657.

To all whom it may concern:

Be it known that I, ALLAN CUNNINGHAM, a subject of the King of England, and resident of the city of Seattle, in the county of King and State of Washington, have invented certain new and useful Improvements in Towing Machines and Methods of Towing, of which the following is a specification.

My invention relates to a method of and 10 apparatus for use in towing vessels. It consists in a method whereby the towing pull or torque is opposed by an electrically produced torque and whereby this electrically produced torque is varied by and in accordance with the variations occurring in the 15 towing torque.

It further consists in apparatus whereby the above results are secured.

It is the object of my invention to provide 20 a method and means whereby the constantly varying pull of a towing line may be satisfactorily taken care of and handled by electrical apparatus.

Another object of my invention is to provide 25 simple, efficient, and convenient forms of apparatus for carrying out my method, which will be economical in power consumed, and sensitive to control in operation.

My invention comprises those novel steps 30 and combinations thereof constituting an improved method of towing, and also those novel parts and combinations thereof which constitute my improved apparatus.

In the accompanying drawings I have 35 illustrated more or less diagrammatically several arrangements for carrying out my improved method.

Figure 1 represents one arrangement, which is the one I most prefer.

40 Figure 2 represents the electrical diagram of this form of apparatus.

Figure 3 represents an alternative arrangement of parts.

45 Figure 4 represents the electrical diagram for this alternative apparatus.

Figure 5 represents a third form of apparatus.

In the form of construction shown in Figures 1 and 2, the towing line 10 is wrapped 50 about a drum, capstan, or winch 1 which is rotatably mounted. An electric motor 2 is connected to the drum 1 to rotate the same. Current is supplied to the motor 2 from any suitable source through the circuit 20. The 55 source which I have shown in these figures is a generator 3. This generator is preferably

separately excited through the exciting circuit 30, and may be rotated by any suitable means acting upon the pulley 31.

In the exciting circuit 30 of the generator 60 I provide one or more variable resistance members shown herein as the rheostats 4 and 5. The rheostat 5 is manually controllable through a suitable handle 51 to set the initial resistance in the field circuit at any 65 given amount. The rheostat 4 has its contact arm 41 connected to be moved or rotated, relative to the fixed contact members 42, from the drum 1. This may be done through suitable gearing, illustrated at 43. 70 By thus connecting the drum and the rheostat 4, means are provided for varying the field resistance according to the direction and amount by which the drum is rotated.

A switch 32 adapted to bridge the rheostat 4 may be employed to cut out this rheostat whenever it is desired to operate the drum free from automatic control. In order to facilitate paying out the line I may provide a reversing switch 21 in connection 75 with the motor 2. I may further provide a brake, indicated at 11, which is electrically controlled through apparatus so connected as to be inoperative while the motor circuit is closed and current is flowing, but which will 80 be included in the motor circuit and become operative whenever the current is shut off, thereby acting to hold the drum 1 in any given position if and when the drum-controlling motor is cut out. 90

The generator 3 should be capable of producing a current which, when applied to the drum motor 2, will produce a torque in the drum equal to the maximum torque produced therein by the tow line. The delivery 95 of this current to the drum motor is, however, controlled so that normally much less than the maximum output is received by the motor 2.

The rheostat, or whatever controlling 100 means are employed, is adjusted so that at a certain basic or normal pull upon the tow line, the torque of the motor acting upon the drum exactly balances the pull of the tow line, and so that as the pull upon the line 105 becomes greater or less than this basic pull, the paying out and taking up of the tow line by the drum changes the amount of current received by the motor 2 and therefore the torque communicated to the drum, this 110 torque decreasing as the line is taken in and increasing as it is paid out. The amount

of current supplied by the generator 3 is controlled by cutting in more or less resistance in the generator field circuit 30. The initial or basic motor torque which counter-
5 balances the towing torque may be set for any given tow line pull by means of the manually operable rheostat 5.

An increase or decrease in the towing torque will produce movement of the drum.
10 If the towing torque is increased, line will be paid out, and if it is decreased slack will be taken up, for the reason that the equilibrium between the motor torque and the towing torque is disturbed. However, such motion of the drum is communicated to the automatic rheostat 4. An increase in the towing torque rotates the contact member 41 of the rheostat 4 to lessen the field resistance of the generator 3 and in this manner the 15 current supplied to the motor, and hence the motor torque, is increased in proportion and opposite in effect to the variation from normal of the towing torque. Line will be paid out until the increase in the motor torque overcomes the increase in the towing torque when the motor 2 will cause the drum 1 to be reversed and the line paid out will again be taken in until the tow and tug have resumed their normal relative positions.
25

30 Assisting the variation in field resistance caused by the action of the rheostat 4 in producing the extra motor torque required to counter-balance the extra towing torque, is the E. M. F. produced in the motor by rotation against the current. This will turn the motor into a generator for the time being, and will produce a tendency to rotate in the direction opposite to the direction in which it is turned by the towing torque. In other 35 words, the motion of the motor armature produces an E. M. F. in the circuit 20 in the same direction as that from the generator, thus further increasing the torque resisting the run out of the cable, in proportion to the speed at which it is run out. As the pull on the towing line 10 decreased, the motor comes to a standstill, reverses, and begins to wind up the cable paid out due to the increased 45 voltage of the generator, at a speed in proportion to the speed of release of the strain, until normal or basic position of the drum is reached and parts are in equilibrium.
50

55 It will be evident that a sudden slackening of the strain upon the line 10 will first permit the motor to take up the slack, the motor torque for the time being overcoming the towing torque. However, as strain is gradually placed upon the line, the two 60 torques will again become equal and, due to the decreased E. M. F. in the motor circuit 20 caused in the manner previously described by such rotation, and by the action of the rheostat 4, the line taken up will again be paid out until the tow and tug again resume their 65 normal relative positions as before.

The motor which is employed must be of a capacity considerably beyond that required to produce the normal motor torque, as it should not require its full load current to produce torque enough to balance the maximum steady pull on the towing line, as the current required fluctuates and the length of time at a standstill with full current flowing will give more than normal heating in the motor.
75

The generator should have commutating poles so as to neutralize the demagnetizing effect of the armature current, which will be of full load order most of the time and also to provide perfect commutation at the lower 80 voltages which will be maintained the greater share of the time. The generator should be equal in continuous current carrying capacity to the motor and should have enough power driving it, at approximately 85 constant speed, to pull in the tow at the required speed. Ordinarily though, this amount of power will not be necessary under towing conditions.

If it is desired to haul in the line 10, the 90 switch 32 may be closed to cut out the automatic rheostat 4 and by manipulation of the manual rheostat 5 the motor 2 may be supplied with sufficient power to haul in the line as desired. If it is desired to pay out 95 line having no strain thereon, the automatic rheostat 4 may be cut out and, by reversing the motor 2 through the reversing switch 21, the towing line may be paid out.

The device shown in Figures 3 and 4 operates in the same manner, but the apparatus is somewhat simpler than that described and shown in Figures 1 and 2, and is in some instances preferable for this reason. In this form of apparatus the drum 1, the motor 2 100 with its reversing switch 21, the automatic rheostat 4 and its connection to the drum 1, and the manual rheostat 5 and switch 32 for cutting out the automatic rheostat, remain the same as has been described in connection 105 with Figure 1. The apparatus is designed, however, for operating directly from direct current mains supplied with current from any suitable source (not shown). The rheostats 4 and 5 in this form are in the motor circuit 22 and control the current supplied to the motor through dissipating in resistance the difference between full voltage and the amount required to produce a motor torque sufficient to counter-balance the towing torque. In this form of apparatus, practically full load current, or sufficient power to haul in the load at full speed, will be consumed all the time the machine is in operation. As there is considerable current passing through the rheostats 4 and 5 these must be made sufficiently heavy to carry this current. They would be considerably heavier than those required in the apparatus shown in Figure 1. This form is advantageous be- 110
115
120
125
130

cause it is possible to eliminate the generator 3 of the previous form, and the motor or engine which would be required to drive it.

In the device shown in Figure 5 the current supplied to the motor 2 is still controlled by a power-varying element but the form of this element differs from that shown in the figures previously described. The power varying element here, instead of a variable-effect generator or main line, consists of a heavy-duty storage battery 6 which supplies a variable amount of power to the motor 2, the amount depending upon certain contact members which are controlled indirectly by the rotation of the drum 1. I prefer that the motor 2 be externally excited through the circuit 60 bridging the entire battery 6.

Instead of an automatic rheostat connected to move with the drum, I employ a selective switch consisting of the bridge member 7 and the individual contact members 71. The bridge member 7 is connected through suitable gearing 72 to be rotated by the drum 1. The individual contact points 71 with which the bridge member 7 selectively contacts, are each connected to its individual contact member 73. These contact members are pivoted by one end and are connected electrically in the motor circuit 24. They are adapted to be swung to close contact each with its individual contact point 64 which is so connected to the battery 6 as to control a different number of cells from all of the other contact points 64.

Closing of the circuit between the members 73 and 64 is controlled from the selective switch members 7 and 71 by means of electro-magnets 75, which are fixed relative to the fixed points 64, and which act upon a magnetic portion 76 of the member 73. The current to each of the electro-magnets 75 is controlled through a circuit 74 leading from its individual contact point 71 to the selective switch, through the magnet 75 to a fixed auxiliary contact point 77, and thence through an auxiliary contact point 78 carried by that swinging member 73 adjacent in the series of contact members to the member 73 about to be closed, and thence back to the individual contact points 71 through a control battery 79 and the bridge member 7. The purpose of this construction is to prevent closing of the contacts 73, 64 controlling a certain portion of the battery 6 until all of the remainder of such contacts have been opened. This prevents short-circuiting of any of the battery cells.

The operation of the device is substantially the same as that described for the two previous constructions. Rotation of the drum 1 rotates the bridge member 7 of the selective switch to control a certain one of the contacts 73, 64, thereby to throw in more or less current from the battery 6 to the

motor 2, and in this manner producing an increase or decrease in the motor torque in conformity with and opposite in effect to the increase in the towing torque.

What I claim as my invention is:

1. In a towing machine, in combination, 70 a drum, an electric motor for producing a torque upon said drum, a source of current to said motor normally supplying sufficient power to maintain the motor torque in 75 equilibrium with and opposite in effect to the towing torque, and a rheostat mechanically operated by said drum and electrically connected in the circuit to said motor, and operable to vary the power delivered to the 80 motor proportionally to the variation from normal of the torque upon the drum, and opposite in effect.

2. In a towing machine, in combination, 85 a drum, an electric motor for rotating said drum, and means for maintaining the torque of said motor normally in equilibrium with the towing torque, said means comprising a rheostat electrically-connected to control the current delivered to the motor and connected mechanically to be moved by said drum, said rheostat being operable to vary the power transmitted to the motor proportionately to the variation from normal 90 of the towing torque upon the drum, and 95 opposite in effect, and a second rheostat in said motor circuit manually operable to control the power delivered to the motor.

3. In a towing machine, in combination, 100 a drum, an electric motor for producing a torque upon said drum normally equal and opposite in effect to the towing torque thereupon, and means operable by movement of the drum for varying the electromotive force in said motor to produce an increase or decrease 105 of motor torque counter and equal to the variation from normal of the towing torque.

4. In a towing machine, in combination, 110 a drum, an electric motor for producing a torque upon said drum normally equal and opposite in effect to the towing torque thereupon, means operable by movement of the drum for varying the electromotive force in said motor to produce an increase or decrease 115 of motor torque counter and equal to the variation from normal of the towing torque, and a brake for said drum in series with the motor and operative while the current is off.

5. In a towing machine, in combination, 120 a drum, an electric motor for producing a torque upon said drum normally equal and opposite in effect to the towing torque thereupon, and a rheostat in the motor circuit and operable by movement of the drum to 125 vary the current supplied, thereby to vary the motor torque in conformity with and opposite in effect to the variation from normal of the towing torque.

6. In a towing machine, in combination, 130

1. a drum, an electric motor for producing a torque upon said drum normally equal and opposite in effect to the towing torque thereupon, and a pair of rheostats in the motor circuit, one being operable automatically by movement of the drum to vary the current supplied thereby to vary the motor torque in conformity with and opposite in effect to the variation from normal of the towing torque, the second rheostat being manually operable to vary the current supplied.
2. In a towing machine, in combination, a drum, an electric motor for producing a torque upon said drum normally equal and opposite in effect to the towing torque thereupon, and a pair of rheostats in the motor circuit, one being operable automatically by movement of the drum to vary the current supplied thereby to vary the motor torque in conformity with and opposite in effect to the variation from normal of the towing torque, the second rheostat being manually operable to vary the current supplied, and means for cutting out said automatic rheostat.
3. In a towing machine, in combination, a drum, an electric motor for producing a torque upon said drum normally equal and opposite in effect to the towing torque thereupon, and a rheostat in the motor circuit and operable by movement of the drum to vary the current supplied, thereby to vary the motor torque in conformity with and opposite in effect to the variation from normal of the towing torque, and a brake for said drum in series with the motor and operative while the current is off.
4. In a towing machine, in combination, a drum, an electric motor for producing a torque upon said drum, and means directly in the motor circuit for varying the power delivered to the motor proportionately with and opposite in effect to the variations from normal of the towing torque upon the drum.
5. In a towing machine, in combination, a drum, an electric motor for producing a torque upon said drum, a source of current to said motor normally supplying sufficient power to maintain the motor torque in equilibrium with the towing torque, and means interposed in the electric circuit between said power source and the motor for varying the power delivered to the motor proportionately to the variation from normal of the towing torque, and opposite in effect.

Signed at Seattle, King County, Washington this 16th day of November 1920.

ALLAN CUNNINGHAM.
